2,549,579

PASTER FOR CIGARETTE MAKING MACHINES

George Dearsley, Scarsdale, N. Y., assignor to
American Machine & Foundry Company, a corporation of New Jersey

Application July 9, 1949, Serial No. 103,853

11 Claims. (Cl. 91—49)

1

This invention relates to paste applying apparatus for cigarette making machines and more particularly to an improved mounting for a paste supplying nozzle.

It is the present practice to extrude a continuous stream of starch paste from a nozzle having a slot which rides against the concave face of a wheel sometimes referred to as a marble wheel. It has been found that starch paste tends to ooze out between the seal formed by the nozzle and the marble wheel unless the fit is particularly close. To obtain a close fit between the nozzle and the marble wheel requires much time. Even after a close fit has been obtained the nozzle and marble wheel sometimes get out of alignment again when the nozzle pressure against the wheel is adjusted to feed paste properly due to the deflection of the supporting member. At the end of each working day and sometimes during the day, the paster nozzle may be removed for purposes of cleaning. When the nozzle is replaced, much time is again frequently lost in properly aligning the nozzle with the marble wheel.

It is therefore an object of my present invention to overcome these alignment problems by providing a mounting which will allow the paster to be readily removed for purposes of cleaning and which will allow it to be accurately replaced at the end of the cleaning process without its getting out of alignment with the marble wheel.

Another object of my invention is to provide a mounting for the nozzle of a cigarette machine paster which will be self centering with respect to a marble wheel when pressure is applied to the nozzle.

A further object of this invention is to provide a slideable mounting for a nozzle which permits it to be readily located over the center of the marble wheel.

Another object is to provide a mounting for the nozzle of a cigarette machine paster which will be so arranged that any deflection that occurs as a result of increasing or decreasing the pressure against the nozzle will not affect the relative position of the nozzle to the marble wheel so as to break the seal therebetween.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

2

Fig. 1 is a side elevation partly in section of the improved paste applying apparatus.

Fig. 2 is an end elevation taken on the line 2—2 of Fig. 1.

5 In the embodiment used to illustrate the invention a gear housing 10 and the cylinder supporting bracket 12 is secured to the frame 14 of a cigarette machine by a suitable means such as bolts (not shown). The worm 16 is driven from the main shaft of a cigarette making machine and imparts driving movement to the worm gear 18. Teeth 20 are formed on the hub 22 of the worm gear 18 and constitute part of a conventional toothed clutch. Similar teeth 24 are formed on the hub 26 of the hand wheel 28 so that driving movement of the worm gear 18 will be imparted to the hand wheel 28 through the teeth 22 and 24 which comprises a toothed type clutch.

10 20 The hand wheel 28 has a key 30 which slidingly engages with the keyway 32 formed along the length of the threaded feed screw 34 so that the hand wheel 28 and screw 34 rotate together. A cap 36 is mounted on one end of the threaded screw

15 25 30 34 and on the other end of the threaded screw 34 is mounted the piston 38. The threads of screw 34 coat with the threaded hole 40 formed in the supporting bracket 12 so that when the hand wheel 28 is rotated either through the worm gear 18 or manually, the screw 34 will raise or lower the piston 38 depending upon the direction the screw 34 is rotated.

35 40 45 Piston 38 is arranged to move up and down inside of a cylinder 42 which contains a paste P such as starch. The lower end of the cylinder 42 has a cap 44 to which is attached a flexible paste conveying tubing 46 while the upper end of the cylinder 42 has a flange 48 secured thereto which supports the cylinder from the top of the bracket 12.

40 45 50 Cylinder 42 is held firmly in bracket 12 by a hinged clamp 50 which is locked in closed position by means of a winged nut 52 pressing against the lugs 56 formed on the hinged door 50. The nut 52 is threaded on a hinged bolt 54 which is secured at its pivoted end to bracket 12. It will thus be seen that when downward movement is imparted to the piston 38 through the screw 34 paste will be forced through the flexible paste conveying tubing 46 to the paste applying member 58. Conventional nipples 60 and 61 are employed for connecting the tubing 46 with the cap 44 and the member 58.

55 The member 58 has a hub 62 which is pivotally and slidably mounted on stud 64. Stud 64 is

fixedly secured to and projects from the framework of a cigarette making machine. Paste is forced through a duct 66 formed along the length of the member 58 which connects with a transverse hole 68. A cover plate 70 is secured to the member 58 by means of suitable screws 72 and has a deflector stud 74 which deflects paste from the hole 66 to the hole 68.

The discharge end of the nozzle casting 58 is provided with a nozzle 73 which has a convex surface 79 which rides in contact with the concave periphery 75 of the marble wheel 76. The convex surface 79 is kept in contact with the marble wheel 76 by suitable means such as the adjusting screw 78 having a lock nut 80. Adjusting screw 78 is threaded in the lug 82 which projects from the frame of the cigarette making machine. It will be noted that the adjusting screw 78 is substantially in line with the plane of rotation of marble wheel 76 and when the screw 78 is set the lines of force will be substantially in line with the center of the marble wheel 76. Any twisting action would occur in the screw 78 and not in the nozzle 74. Therefore there would be no tendency to break the seal between the face of the nozzle 74 and the marble wheel 76 as often occurred heretofore when the pressure of the nozzle against the marble wheel was adjusted.

It will be further noted, as seen in Figs. 1 and 2, that the hub 62 of the member 58 is slidably and pivotally mounted on the stud 64 so that the nozzle 74 is free to move transverse to the plane of rotation of marble wheel 76. This permits the nozzle 74 to automatically center itself with respect to the marble wheel 76 when pressure is applied and prevents the nozzle from having any tendency to tilt. To obtain the best results the screw 78 should be preferably adjusted when the cigarette machine is running.

Marble wheel 76 is mounted on shaft 84 which is driven from the main shaft of the cigarette making machine. A paste applying transfer wheel 86 is provided for removing paste from the periphery of the marble wheel 76 and transferring it to the seam L of the cigarette rod R. The transfer wheel 86 is driven by the shaft 88 from the main shaft of the cigarette making machine.

The operation of my invention may be briefly described as follows:

Prior to starting the cigarette making machine in operation the cylinder 42 is removed and filled with paste. This is accomplished by lifting the hand wheel 28 upwardly to disengage the toothed clutch 24 and 20 and then turning the hand wheel 28 counterclockwise until the piston 38 has reached the upper limit of its travel. After releasing the nipple 61 from the cylinder cap 44 the wing nut 52 is then unscrewed so that the bolt 54 can be swung outwardly to release the lugs 56 of the hinge clamp 50.

After the cylinder 42 has been cleaned and refilled with paste it is replaced in the supporting bracket 12. The hinged door 50 is then closed and the bolt 54 is swung into place and the nut 52 tightened against the lugs 56 to hold the door 50 in place. The cylinder 42 will be then suspended by means of flange 48 from the top of bracket 12 and the hinged door 50.

Nipple 60 is then secured to the member 58 as shown in Fig. 1. By rotating the hand wheel 28 clockwise the piston 38 will move downwardly until it comes into contact with the paste P in the cylinder 42. Hand wheel 28 is then lowered to engage the toothed clutch 24 and 20.

When the cigarette machine is in operation it

causes the worm 16 to rotate slowly which in turn imparts rotary movement to the worm gear 18. Through the teeth 20 engaging with the teeth 24 the hand wheel 28 is rotated. By means of the key 30 the feed screw 34 is rotated forcing the piston 38 to move downwardly which in turn causes paste to flow through the flexible tubing 46 into the ducts 66 and 68 of the member 58. The rotating marble wheel 76 receives paste extruded through duct 68 and orifice 71 of nozzle 78 and carries it to a point where the periphery of the transfer wheel 86 picks up the paste and deposits it on the lap edge L of the traveling cigarette rod R.

15 The paste extruding nozzle casting 58 may be readily removed and replaced as follows:

Lock nut 80 is turned counterclockwise to release the adjusting screw 78. Adjusting screw 78 can then also be turned counterclockwise thus 20 removing pressure from the cover plate 70. After unscrewing nipple 61 from the cylinder cap 44 the operator merely has to slide the hub 62 off the stud 64 to release the member 58 so that it may be cleaned.

25 To replace the member 58 the operator slides the hub 62 over the stud 64 and moves it inwardly until the orifice 71 of nozzle 73 is in the center of the marble wheel 75. Adjusting screw 78 is then turned clockwise to press against the cover plate

30 70 to hold the nozzle 73 against the concave surface of the marble wheel 76. When the adjusting screw 78 is turned to apply pressure to the member 58 the lines of force will pass through the center of the nozzle contacting surface 74 and the concave surface of marble wheel 75 thereby avoiding any tendency for either of these members to twist. Since the hub 62 is slidably mounted on the stud 64 it permits the nozzle contacting surface to automatically seek the 35 center of the concave surface of the marble wheel 76 when the latter starts to rotate.

40 It will thus be seen that I have provided a mounting for the nozzle of a cigarette machine paster which is adapted to be not only quickly removed for purposes of cleaning but which can be quickly replaced without loss of time and properly align itself when the machine is started. As just mentioned since the lines of force are in direct alignment there is no tendency for the 45 nozzle to twist when pressure is applied which results in paste escaping between the marble wheel 76 and the convex nozzle surface 74.

45 While applicant's invention is especially well suited for use with a starch paste which may have a relatively high viscosity it is obviously 50 also adaptable for use with a paste such as casein which may have a lower viscosity. The primary feature of applicant's invention consists of the particular mounting and arrangement of the paste applying nozzle which permits the same to 55 be quickly removed and replaced without an operator encountering any difficulties in aligning the paste applying nozzle 74 with the marble wheel 76.

60 The invention above described may be varied in construction within the scope of the claims, for the particular device selected to illustrate the invention is but one of many possible embodiments of the same. The invention, therefore, is not to be restricted to the precise details of the structure shown and described.

65 What is claimed is:

70 1. A mounting for the paste applying nozzle of a cigarette making machine comprising, a fixed stud connected to the framework of a cig-

arette making machine and arranged in parallel with the shaft of a paste receiving marble wheel, a paste extruding nozzle slidably and pivotally mounted on said stud, and a clamp screw for holding said nozzle against said marble wheel by applying pressure at a point on said nozzle whereby the nozzle will be substantially in line with the clamp screw and the center of the shaft supporting the marble wheel.

2. A mounting for the paste extruding nozzle of cigarette making machine, comprising, a stud fixedly secured to the framework of a cigarette making machine, a paste extruding nozzle pivotally and slidably mounted on said stud and having a discharge orifice adapted to ride in contact with the surface of a paste receiving marble wheel, a clamp screw for holding said orifice against said marble wheel, said clamp screw being arranged to apply pressure to said nozzle at a point which will be substantially in line with the discharge opening of said nozzle and the center of the marble wheel shaft.

3. A support for the paste extruding nozzle of a cigarette making machine comprising, a rotating shaft, a wheel fixedly mounted on said shaft and having a concave surface formed along its periphery, a stud spaced from the shaft of said marble wheel and arranged in parallel therewith, a paste extruding nozzle pivotally and slidably mounted on said stud and having a discharge orifice adapted to ride on top of the concave surface of said wheel and a clamp screw for applying pressure to said nozzle at a point which will be directly in line with the center shaft of said wheel and said discharge orifice.

4. A support for the paste extruding nozzle of a cigarette making machine comprising, a rotating shaft, a wheel having a concave periphery fixedly mounted on said shaft, a stationary stud spaced from said shaft and arranged in parallel therewith, a paste extruding nozzle having a convex paste discharging surface for engaging in contact at right angles with said concave periphery, means for pivotally and slidably connecting said paste extruding nozzle to said stud, a clamp screw positioned perpendicularly above said discharge orifice for applying pressure to said nozzle to hold it in contact with the concave surface of said wheel, means for forcing paste through said discharge orifice onto the periphery of said wheel and means for transferring the paste discharged on the concave surface of said wheel to the lap edge of a traveling cigarette rod.

5. In a cigarette making machine having a paste extruding nozzle, and a wheel having a concave surface with which said paste extruding nozzle engages, a support for said nozzle comprising, a fixed stud arranged in parallel with the axis of rotation of said wheel, means for pivotally connecting said paste extruding nozzle with said stud, a clamp screw for pressing said paste extruding nozzle against the concave surface of said wheel, said clamp screw applying force to said nozzle in a direction which will be substantially in line with the discharged orifice of said nozzle and the center of said shaft.

6. In a cigarette making machine, a marble wheel having a concave paste receiving surface, a paste extruding nozzle having a concave surface adapted to ride in contact with the concave surface of said paste receiving marble wheel, a fixed stud connected to the framework of a

cigarette making machine and arranged in parallel with the shaft of a paste receiving marble wheel, an arm for slidably and pivotally mounting said nozzle on said stud for movement transverse to the plane of rotation of said marble wheel, and means for holding said nozzle against said marble wheel.

7. In a cigarette making machine having a paste extruding nozzle formed with a convex surface and a paste receiving wheel having a concave surface with which said paste extruding nozzle engages, a support for said nozzle comprising a stud fixed to the frame of the cigarette making machine and arranged transversely to the plane of rotation of said wheel, means for connecting said nozzle to said stud for free slidable movement along a path transverse to the plane of rotation of said wheel, and means for holding the convex surface of said nozzle against the concave surface of said marble wheel.

8. In a cigarette making machine, a paste extruding nozzle having a convex surface, a paste receiving wheel having a concave surface, an arm supporting said nozzle at one end thereof, a pivot for supporting the other end of said arm for slidabale movement across the plane of rotation of said marble wheel and means for urging the convex surface of said nozzle against the concave surface of said marble wheel.

9. A support for the paste extruding nozzle of a cigarette making machine comprising, a rotating shaft, a wheel fixedly mounted on said shaft and having a convex surface formed along the periphery thereof, a pivot spaced from the shaft of said marble wheel and arranged in parallel therewith, a paste extruding nozzle pivotally and slidably mounted on said pivot and having a discharge orifice adapted to ride on top of the concave surface of said wheel and means for urging said nozzle against said wheel.

10. In a cigarette making machine having a paste extruding nozzle, a mounting therefor comprising a paste receiving marble wheel rotatable in a predetermined plane of rotation and having a concave surface for receiving paste, a paste extruding nozzle having a convex surface adapted to ride in contact with the concave surface of said marble wheel, a support for said nozzle permitting free transverse movement across the plane of rotation of said marble wheel and for movement along the plane of rotation of said marble wheel, and mechanism for urging the convex surface of said nozzle against the concave surface of said marble wheel.

11. In a cigarette making machine, a paste receiving wheel having a concave surface, a nozzle having a convex surface adapted to ride in contact with said paste receiving wheel, a mounting for preventing said nozzle from twisting while maintaining said nozzle free for lateral movement across the plane of rotation of said marble wheel, and means for urging said nozzle against the concave surface of said marble wheel.
